UNITED STATES PATENT OFFICE.

HARRY R. MAXON, OF MUNCIE, INDIANA.

PROCESS FOR THE COMBUSTION OF GAS.

1,291,589.

Specification of Letters Patent. Patented Jan. 14, 1919.

Application filed March 16, 1918. Serial No. 222,829.

To all whom it may concern:

Be it known that I, HARRY R. MAXON, a citizen of the United States, residing at Muncie, in the county of Delaware and State 5 of Indiana, have invented certain new and useful Improvements in Processes for the Combustion of Gas, of which the following is a specification.

Prior to this invention the most usual 10 method of burning gas for heating purposes has been to mix the gas with a certain proportion of air, insufficient for perfect combustion, and feed the mixture so formed to a burner at the desired location where 15 additional air is supplied either from the surrounding atmosphere or by injection to completely consume the fuel gas. The gas or air or both are injected under considerable pressure and so discharged from the 20 burner, and as the mixture has to take up from the surrounding atmosphere sufficient air to complete the combustion ignition does not take place directly at the orifice of the 25 burner but at a distance therefrom depending upon the pressure of the mixture and the access of additional air. The length of the flame is governed by the distance the mixture is required to go before picking up sufficient air to complete the combustion. It 30 has generally been recognized that for most purposes a so-called slow, lazy flame is desirable, to wit, one which moves slowly, ignites directly at the nozzle of the burner, and immediately burns throughout in a 35 broad comparatively short flame. With this in view the effort has been made to feed to the burner a mixture of air and combustible gas in the required proportions for economical and efficient combustion by mixing the 40 air and gas in the required proportions at some distance from the burner, injecting the gas as usual under considerable pressure, thereby causing a more or less complete mixture and forcing the mixture to the burner. 45 There is, however, always danger in such devices of the "striking back" of the flame through the burner and conduit which has been met with more or less success by interposing in the conduit leading to the burner 50 gauze or other material adapted to obstruct the flow, and exerting sufficient pressure to drive the mixture at a speed in excess of that at which the combustion of the gas could travel backward from the burner. 55 This is objectionable, however, because of the high pressure necessary, and the incom-

plete mixture of the combustible gas and air. In my improved process the combustible gas and air are introduced into a mixing device at very low pressures, the air preferably being at atmospheric pressure or less, and the gas but slightly above atmospheric pressure. The mixture thus formed is fed by the mixing device, which may be in the nature of a fan, through a large unobstructed conduit by which the low pressure of the mixture is preserved to the burner where it is burned, preferably without substantial access of additional air.

A great variety of apparatus may be employed for practising my invention, but in the accompanying drawing I have shown a device suitable for the purpose and which forms the subject-matter of my co-pending application Serial No. 124,747, filed October 9, 1916. Referring to the drawing, Figure 1 is a front elevation of a furnace having my invention applied thereto; and Figs. 2 and 3 are side and front elevations, respectively, of the mixing device used in connection therewith, Fig. 2 being partly in section to better show the construction.

In the specific device shown in Fig. 1 my invention is applied to a plurality of furnaces, the furnace structure 4 being shown as of an ordinary type and provided with burners 5 which are individually supplied with combustible gas mixture from several fans 6. The construction of the furnace is such that there is no substantial supply of outside air. The fans, except in the respects hereinafter pointed out, are of usual or ordinary construction receiving their supplies of gas and air about their axes and discharging them tangentially. The casing 8 is therefore formed with a central opening at one side to which is connected a neck 13 of large diameter, the outer end of which receives a large gas pipe 11 controlled by a hand valve 12. A valve 10 of a well known type surrounds the pipe 11 and is adjustable thereon to regulate the supply of air to the fan. In the construction shown the air is taken directly into the fan casing from the atmosphere, though obviously, provided the air is not put under too much pressure, it might be led through a conduit of considerable length and if desired preliminarily heated.

The gas as heretofore noted is introduced in large volume at very low pressure and the same is true of the air. Partly because of

the low pressure it is necessary to mechanically mix the air and gas in order to get the mixture thorough, and this is done in the casing of the fan before the mixture is led away to the burner. The conduit by which the mixture is conveyed to the burner is as heretofore observed of large capacity and unobstructed whereby the inflammable mixture is maintained at a low pressure. In its flow through the conduit to the burner its low pressure is maintained and the speed of flow is such merely as to prevent striking back. It is thus admitted to the furnace substantially at the furnace pressure, completely mixed throughout so that when it is subjected to the ignition temperature of the furnace it immediately is ignited throughout and burns with a broad lazy flame.

I claim:

- 20 1. A process for the combustion of gas

which consists in supplying gas and air to a mixer, regulating the gas and air to the relative proportions required for complete combustion, mixing the gas and air, conducting the resultant mixture to a burner, burning the mixture, and maintaining the speed of flow of the mixture at the lowest rate necessary to prevent back firing.

2. In a process for the combustion of gas supplying air and gas to a mixer, the former at a low pressure and the latter at substantially atmospheric pressure, regulating the gas and air to the relative proportions required for complete combustion, mixing the gas and air, conducting the resultant mixture to a burner, burning the mixture, and maintaining the speed of flow of the mixture at the lowest rate necessary to prevent back firing.

HARRY R. MAXON.
